ANCHOR FOR PLURAL ELECTRIC CONDUCTORS

Carl H. Judisch, Hamden, Conn., assignor to The Whitney Blake Company, Hamden, Conn., a corporation of Connecticut

Application January 13, 1945, Serial No. 572,661

5 Claims. (Cl. 173—322)

1

The present invention relates to improvements in anchors for plural electric conductors, i. e., anchor-means whereby plural electric conductors may be firmly held against axial displacement.

One of the objects of the present invention is to provide superior anchor-means whereby plural electric conductors may be securely held against axial displacement without requiring the knotting of the conductors.

Another object of the present invention is to provide superior anchor-means whereby plural electric conductors may be anchored to a body of insulating-material, despite poor adhesion between the insulation of the conductors and the said body of insulating-material and without requiring the knotting of the conductors.

A further object of the present invention is to provide superior anchor-means especially suited for anchoring plural electric conductors of the type wherein the individual conductors are each provided with an insulating-coating which is separably-adhered to the insulating-coating of an adjacent conductor.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a view in side elevation of a bushing-like body of insulating-material having double insulated electric conductors anchored thereto, in accordance with the present invention;

Fig. 2 is a central-longitudinal sectional view thereof taken on the line 2—2 of Fig. 1 but with the electric conductors and the anchoring-member in elevation;

Fig. 3 is a central-longitudinal sectional view taken on the line 3—3 of Fig. 2 but with the electric conductors and the anchoring-member in elevation;

Fig. 4 is a transverse sectional view taken on the line 4—4 of Fig. 1; and

Fig. 5 is a transverse sectional view corresponding to Fig. 4 but showing a modified form of the present invention in which the separate anchoring-member is omitted.

The assembly illustrated in Figs. 1 to 4 inclusive of the accompanying drawings, includes a bushing 10, a plate-like anchoring-member 11 and two electric conductors 12 and 13 each composed in the instance shown, of a plurality of

2

relatively-fine strands of wire and respectively provided with coatings of insulation 14 and 15.

The bushing 10 above referred to constitutes what may be termed a "holding-body" and may be formed of any suitable material, though it is preferable that it be formed of material which is both resilient and insulating such, for instance, as rubber, synthetic rubber, or any one of the wide variety of synthetic plastics. The said bushing is preferably provided about midway of its length with an annular groove 16 for purposes as will hereinafter appear. The respective opposite ends of the bushing 10 taper away from the groove 16 and inwardly to provide two oppositely-sloping conically-contoured portions 17 and 18 each of which has a diameter at its outer end which is smaller than the diameter of the bottom-wall of the annular groove 16. The proportioning just referred to is such that when it is desired to insert the resilient bushing 10 and the attached electric conductors 12 and 13 through an aperture in a panel or the like, one of the outer ends of the bushing will provide the desired lead-in and permit the bushing to be readily inserted into the aperture so as to compress the resilient material of which the said bushing is formed, until such time as the groove 16 or its equivalent is brought into alignment with the panels, whereupon the resilient material will spring outwardly and the bushing will be firmly held in place in the panel by the entry of the latter into the groove 16.

In the instance shown, the respective coatings of insulation 14 and 15 of the electric conductors 12 and 13, are normally adhered together at their adjacent faces in a manner well known in the art, though obviously other forms of plural conductors may be utilized in connection with the present invention.

40 The plate-like anchoring-member 11 may be formed of any suitable material such, for instance, as indurated fiber and is totally embedded within the bushing 10 for purposes as will hereinafter appear.

45 In producing the assembly above referred to, an intermediate portion of the assembly comprising the two electric conductors 12 and 13, together with their respective coatings of insulation 14 and 15, may be separated laterally and the anchoring-member 11 inserted therebetween into substantially the relationship illustrated in the drawings. Now by means of any suitable molding operation, the bushing 10 or its equivalent may be molded around the spread-apart portions of the electric conductors 12 and 13 and the

anchoring-member 11 and preferably in such manner that the insulating-material of the bushing flows into the voids between the parts 11, 14 and 15.

In the manner above described and illustrated in Figs. 1 to 4 inclusive of the accompanying drawings, the electric conductors 12 and 13 are firmly anchored against axial displacement with respect to the bushing 10, even should there be substantially no adhesion between the coatings of insulation 14 and 15 and the material from which the bushing 10 is formed. As endwise pull is exerted on the electric conductors 12 and 13, which might tend to axially displace the said conductors with respect to the bushing 10, any tendency of the conductors to further separate laterally by being forced apart by the anchoring-member 11, is effectively resisted by the encircling portions of the bushing 10.

In addition to serving as an anchoring-member, the part 11 serves during the molding of the bushing 10 or its equivalent, to hold the desired portions of the electric conductors 12 and 13 apart, to thus permit the entrance of the material being molded into the voids between the parts 11, 14 and 15.

In Fig. 5, the anchoring-member 11 has been omitted from between the laterally-spaced-apart portions of the electric conductors 12 and 13, with the result that when the bushing 10 or its equivalent is molded around the said laterally-spaced-apart portions, an anchoring-web 19 will be formed which is integral with the remainder of the bushing 10 and which will effectively anchor the electric conductors 12 and 13 against axial movement relative to the bushing 10 or its equivalent.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In combination, a molded bushing comprising a body-portion having a pair of sinuous conductor passages extending longitudinally therethrough, the corresponding ends of said pair of sinuous passages intersecting at opposite ends respectively of said bushing and the respective portions of said sinuous passages intermediate the opposite ends thereof being spaced apart laterally to form a substantially-solid web therebetween within the body of said bushing; and a pair of insulated electric conductors molded in situ in said sinuous passages, each insulated conductor being of a diameter to make continuous peripheral engagement with the walls of its respective passage so as to bind with the walls of said web when said insulated conductors are pulled in the direction of their longitudinal axes, whereby said insulated conductors are anchored in said passages against axial displacement with respect to said bushing.

2. In combination, a molded bushing comprising a body-portion having a pair of sinuous conductor passages extending longitudinally therethrough, the corresponding ends of said pair of sinuous passages intersecting at opposite ends respectively of said bushing and the respective portions of said sinuous passages intermediate the opposite ends thereof being spaced apart lat-

erally to form a web therebetween within the body of said bushing, a pair of insulated electric conductors molded in situ in said sinuous passages, each insulated conductor being of a diameter to make continuous peripheral engagement with the walls of its respective passage so as to bind with the walls of said web when said insulated conductors are pulled in the direction of their longitudinal axes; and an indurated-member molded in situ in said web between the laterally spaced portions of said sinuous passages to hold the outer walls of said web spaced apart laterally, whereby said insulated conductors are anchored in said passages against axial displacement with respect to said bushing.

3. In combination, a molded bushing comprising a body-portion having a pair of sinuous conductor passages extending longitudinally therethrough, the corresponding ends of said pair of sinuous passages intersecting at opposite ends respectively of said bushing and the respective portions of said sinuous passages intermediate the opposite ends thereof being spaced apart laterally to form a web therebetween within the body of said bushing, a pair of insulated electric conductors extending continuously through and molded in situ in said sinuous passages, each insulated conductor being of a diameter to make continuous peripheral engagement with the walls of its respective passage so as to bind with the walls of said web when said insulated conductors are pulled in the direction of their longitudinal axes; and an indurated-member molded in situ in said web between the laterally spaced portions of said sinuous passages to hold the outer walls of said web spread apart laterally, whereby said insulated conductors are anchored in said passages against axial displacement with respect to said bushing.

4. In combination, a molded bushing comprising a body-portion having a pair of sinuous conductor passages extending longitudinally therethrough, the corresponding ends of said pair of sinuous passages intersecting at opposite ends respectively of said bushing and the respective portions of said sinuous passages intermediate the opposite ends thereof being spaced apart laterally to form a web therebetween within the body of said bushing, a plural insulated electric conductor molded in situ in said bushing, said plural insulated electric conductor being split longitudinally and spread apart laterally intermediate the opposite intersecting ends of said sinuous passages to provide a single insulated conductor in each passage, each insulated conductor being of a diameter to make continuous peripheral engagement with the walls of its respective passage so as to bind with the walls of said web when said plural insulated conductor is pulled in the direction of its longitudinal axis; and an indurated-member molded in situ in said web between the laterally spaced portions of said sinuous passages to hold the outer walls of said web spread apart laterally, whereby each insulated conductor is anchored in its passage against axial displacement with respect to said bushing.

5. In combination, a molded bushing comprising a body-portion having a pair of sinuous conductor passages extending longitudinally therethrough, the corresponding ends of said pair of sinuous passages intersecting at opposite ends respectively of said bushing and the respective portions of said sinuous passages intermediate the opposite ends thereof being spaced apart laterally to form a web therebetween within the body of

said bushing, a plural insulated electric conductor molded in situ in said bushing, said plural insulated electric conductor being split longitudinally and spread apart laterally intermediate the opposite intersecting ends of said sinuous passages to provide a single insulated conductor extending continuously through each of said passages, each insulated conductor being of a diameter to make continuous peripheral engagement with the walls of its respective passage so as to bind with the walls of said web when said plural insulated conductor is pulled in the direction of its longitudinal axis; and an indurated-member molded in situ in said web between the laterally spaced portions of said sinuous passages to hold the outer walls of said web spread apart laterally, whereby each insulated conductor is an-

chored in its passage against axial displacement with respect to said bushing.
